P. GARDNER.
RIBBON PACKAGE.
APPLICATION FILED MAY 15, 1914.

1,112,062.

Patented Sept. 29, 1914.

UNITED STATES PATENT OFFICE.

PERCY GARDNER, OF NEW YORK, N. Y., ASSIGNOR TO GARDNER & HIGHET CO., OF NEW YORK, N. Y., A CORPORATION OF NEW YORK.

RIBBON-PACKAGE.

1,112,062.

Specification of Letters Patent. Patented Sept. 29, 1914.

Application filed May 15, 1914. Serial No. 838,897.

To all whom it may concern:

Be it known that I, Percy Gardner, a citizen of the United States, residing in the city of New York, borough of Manhattan, 5 in the county and State of New York, have invented a certain new and useful Improvement in Ribbon-Packages, of which the following is a specification.

The invention relates to packages containing ribbons or analogous reeled merchandise in condition for sale in short lengths as required by the retail trade, and the object of the invention is to provide a package in which the reel or roll of ribbon 15 is mounted and protected against damage by soiling, with an exposed end or area attractively presented for inspection.

Another important object is to provide means whereby the roll is completely inclosed in a container and the required short 20 length of ribbon may be easily and quickly drawn from the roll and any surplus be easily rewound without directly handling the roll, thus preserving the freshness of 25 the reeled portion and protecting it from fading through exposure to the light.

The invention consists in certain novel features and details of arrangement and construction by which the above objects are 30 attained, to be hereinafter described and claimed.

The accompanying drawings form a part of this specification and show the invention as it has been carried out in practice. 35 Figure 1 is a perspective view of the improved package. Fig. 2 is a top or plan view of the same. Fig. 3 is a side elevation, certain portions being broken away to show the parts within, and partly in vertical section. Fig. 4 is a vertical section taken on the line 4-4 in Fig. 2. Fig. 5 is a vertical transverse section taken on the line 5-5 in Fig. 4. Fig. 6 is a horizontal section taken on the line 6-6 in Fig. 3. Fig. 7 is a face 45 view of the roll and its core. Fig. 8 is a corresponding view of one of a pair of disks for inclosing the roll. Fig. 9 is a face view of a cylindrical block or center on which the roll and disks are rotatably mounted with- 50 in the container. Fig. 10 is a face view of the annular core alone, on which the roll of ribbon is wound.

Similar letters of reference indicate the same parts in all the figures.

55 The container is a flat rectangular box of

heavy paper, preferably of the folding or knock-down type, having an internal width somewhat in excess of the width of ribbon to be inclosed, and its other dimensions greater than the diameter of the roll or coil 60 in which the ribbon is wound, one edge or top face having slots corresponding to the width of the ribbon, through which the end of such ribbon is threaded with a portion exposed for inspection and a loose end conveniently presented for drawing from the contained roll any desired length. The traverse of the ribbon through the slots offers sufficient tension to hold the end in position, and the location of the slots insures correct 70 rewinding of the surplus.

A are the sides of the box or container, and B B the ends provided with the usual stiffening flaps C C bent inwardly between the sides and held by folding over the top 75 D and bottom E and tucking in the flaps F and G thereon in the usual manner to maintain the rectangular form. The top D is provided with three narrow transverse slots d, d¹ and d² having a length equaling the 80 width of the ribbon to be inclosed.

The ribbon M is wound on a stiff annular core H of fiber-board or heavy pasteboard, of the same width as the ribbon and having an internal diameter to match loosely upon 85 a cylindrical block J, preferably of wood, wider than the ribbon and its core and of the same width as the interior of the container. The ends of the block project on each face beyond such core when the latter 90 and its roll are mounted thereon.

K K are annular disks each having an opening k matching to the block J and adapted to apply one on each face of the roll of ribbon, and of such diameter as to 95 match to and be received easily within the container. The thickness of the disks K K corresponds to the projecting ends of the block J so that when thus assembled and inserted within the container the disks and 100 block, with the inclosed core and roll of ribbon practically fill the container. The parts are secured therein by suitable fastening means, preferably the wire staples L L, driven into the ends of the block J through 105 the sides A A of the container, as shown.

The free end of the ribbon M leaves the roll at the slot d and is passed therethrough to the upper face of the top D, thence downwardly through the slot d¹ to 110

the under face of the top, and again upwardly through the slot d^2 ; the top is then folded down and its flap F inserted between the outer face of one of the disks K and the inner face of the adjacent side A of the container, with a portion of the ribbon exposed between the slots d and d^1 and the free end hanging loosely from the slot d^2 but held by the tension afforded by the tortuous path followed by the ribbon through the slots. By grasping the free end any desired length may be drawn from the roll, the latter with its core H revolving on the relatively fixed block J as a center. The disks K K develop sufficient friction against the sides A A of the container to resist the tendency to revolve with the roll, and usually remain stationary while the roll is thus unwound, but may rotate therewith.

The sides A A are provided with oppositely located curved slots or long apertures $a a$ through which the tips of the finger and thumb may be inserted and the disks K K, which close the apertures, be grasped between them with sufficient pressure upon the inclosed roll to cause the latter to rotate with the disks as they are thus moved in the reverse direction by the fingers and rewind any protruding length or surplus previously unwound in making a sale.

The length of the slots d , d^1 and d^2 should be the same as, or but little greater than, the width of the contained ribbon, and their location should match as closely as practicable to the space between the disks K K to insure a correct return to the roll and avoid wrinkling or other damage in rewinding. One size of container will serve with several widths of ribbon, by employing blocks of uniform width matching such container and applying disks of various widths or thicknesses to fill the spaces between the ribbon roll and side walls A A of the container.

The package protects the roll from the fading action of light and damage by handling and also avoids the necessity for the protective strip of paper usually wound with the ribbon. The disks K K prevent the entrance of light or dust through the apertures $a a$, and permit the roll to be rewound without direct contact of the finger tips with the ribbon. The tension provided by the traverse through the slots d , d^1 , d^2 holds the free end reliably and presents the short length or area of ribbon between the slots d and d^1 smoothly and attractively for inspection, and with the friction of the disks against the close fitting walls of the container, holds the roll against accidental un winding.

I claim:—

1. In a ribbon package, a container, a cylindrical block secured therein, disks rotatably mounted on said block, a roll rotatably mounted on said block between said

disks and having a free end of ribbon presented on the exterior of such container.

2. In a ribbon package, a container having sides and top, disks rotatably mounted in said container, and a roll rotatably mounted between said disks, said top having transverse slots through which the free end of ribbon from said roll is traversed to present an area for inspection and to hold such end. 75

3. In a ribbon package, a container having sides and top the latter provided with a slot, a cylindrical block in said container extending from side to side thereof and secured to said sides, a roll of ribbon rotatably mounted on said block and of less width than the latter, disks rotatably mounted on said block on each side of said roll and filling the spaces between said roll and the adjacent sides, said roll having a free end of ribbon extending through such slot in the top to the exterior of such container. 80

4. In a ribbon package, a container having sides and top, disks rotatably mounted in said container, and a roll rotatably mounted between said disks, said top having transverse slots through which the free end of ribbon from such roll is traversed to present an area for inspection and to hold such end, said sides having apertures closed 95 by said disks and permitting the latter to be grasped for rewinding said roll.

5. In a ribbon package, a container having sides and top the latter provided with a slot, a cylindrical block in said container 100 extending from side to side thereof and secured to said sides, a roll of ribbon rotatably mounted on said block and of less width than the latter, disks rotatably mounted on said block, one on each side of said roll and filling the spaces between said roll and the adjacent sides, said roll having a free end extending through said slot in the top to the exterior of said container, and said sides having apertures closed by said disks 110 and permitting said disks with said roll to be grasped for rewinding. 110

6. In a ribbon package, a container having sides and top, a cylindrical block in said container extending from side to side thereof and secured to said sides, a roll of ribbon rotatably mounted on said block and of less width than the latter, disks rotatably mounted on said block, one on each side of said roll and filling the spaces between said roll and the adjacent sides, said top having three transverse slots therein having a length corresponding to the width of said roll and located immediately above said roll, said roll having a free end extending through said slots to present an area for inspection and to hold such free end. 115

7. In a ribbon package, a container having sides and top, a cylindrical block in said container extending from side to side there- 120

125

of and secured to said sides, a roll of ribbon rotatably mounted on said block and of less width than the latter, disks rotatably mounted on said block, one on each side of 5 said roll and filling the spaces between said roll and the adjacent sides, said top having three transverse slots therein having a length corresponding to the width of said roll and located immediately above said roll, 10 said roll having a free end extending through said slots to present an area for inspection on said top, and said sides having apertures closed by said disks and permitting said disks with said roll to be 15 grasped for rewinding.

8. In a ribbon package, a container having sides and top the latter provided with a slot, a cylindrical block in said container

extending from side to side thereof and secured to said sides, an annular core 20 rotatably mounted on said block and of less width than the latter, a roll of ribbon wound on said core and of the same width as said core, disks rotatably mounted one on each side of said roll and core and filling the 25 spaces between such roll and core and the adjacent sides, said roll having a free end extending through said slot in the top to the exterior of such container.

In testimony that I claim the invention 30 above set forth I affix my signature, in presence of two witnesses.

PERCY GARDNER.
